CPC A61B 2018/0047; A61B 2018/0452; A61B
2018/202; A61B 2018/00476; A45D
26/0004-0009

FIG. 1 is a perspective view of a hair removal device showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken line immediately adjacent the solid contour line along the bottom illustrates the boundary of the claim. The remaining broken lines illustrate portions of the hair removal device. None of the broken line disclosure forms part of the claimed design.
